UNITED STATES PATENT OFFICE

HARRY VISSERING, OF CHICAGO, ILLINOIS, ASSIGNOR TO THE OKADEE COMPANY, OF CHICAGO, ILLINOIS, A CORPORATION OF ILLINOIS

OUTLET VALVE

Application filed June 14, 1924. Serial No. 719,938.

The invention relates to outlet valves for locomotive cylinders, and its object is to provide an improved combined blow-off cock and automatic valve by which the condensate will be drained from the cylinder whenever there is no pressure in the cylinder.

The invention consists in the several novel features hereinafter set forth and more particularly defined by the claims at the conclusion hereof.

In the drawing: Fig. 1 is a diagrammatic view showing the manner in which the improved valves are connected to the steam-cylinder of a locomotive. Fig. 2 is a vertical section. Fig. 3 is a section taken on line 3—3 of Fig. 2. Fig. 4 is a section taken on line 4—4 of Fig. 2.

The invention is exemplified in a structure comprising a casing or body 5 which is connected by a threaded nipple 6 to the engine cylinder 8. An outlet port 7 formed in the cylinder is in communication through the nipple 6 with a chamber or passage 9 in the upper portion of said casing. A valve-seat 10 is formed at the upper end of vertical outlet passage 11, which is formed in the casing 5 and leads downwardly from said seat to an outlet 12 in one side of said casing. A conical cock 13 is adapted to close on seat 10 and has a pendant stem 14 having a deflector cone 15 thereon. The lower enlarged end 14^a of said stem slides in a cylindrical guideway 5^a. A slot 16 is formed in the lower end of the stem for a slide 17 which is adapted to be manually operated to lift the cock 13 above its seat to permit the pressure from the cylinder to escape through passage 11 and outlet 12.

A duct 18 is formed in the casing 5 and leads laterally and outwardly from the chamber 9, thence downwardly, as at 18^a, and thence inwardly, as at 18^b, to upwardly facing outlet 20. A conical valve seat 21 for a ball valve 22 is formed adjacent the upper end of outlet 20. Valve 22 is adapted to be opened by gravity, is guided vertically by ribs 23, and is insertable into and removable from the casing through an opening in the bottom wall 25. A screw plug 24 threaded 50 to the lower wall 25 of said casing closes said

opening. While there is steam in the cylinder, the pressure therein will keep the valve 22 closed, the minimum operating pressure being sufficient to hold the valve 22 up against its seat 21.

The device described forms a combined blow off cock and drain valve. A combined cylinder cock and drain valve is connected to either end of the cylinder to blow off from and drain the cylinder at both 60 sides of the piston. The cocks 13 are conjointly operable by a slide 17 which extends through the stems 14 of both cocks respectively and is provided with a cam 27 for lifting each of said stems. The usual link 28 65 and lever 29 may be used to shift the slide to open the cylinder-cocks 13.

In practice, the cocks are opened whenever it is desired to release the pressure from the cylinder, and closed when the pressure 70 has escaped. They are not generally left open any longer than is necessary to blow off the pressure in the cylinder so that after the valve is closed the condensate accumulates. In the operation of the present invention, the ball valve 22 will be held closed while there is pressure in the cylinder 8. When the cocks 13 are opened the pressure drops so that the ball 22 will fall by gravity onto plug 24 and remain there. The condensate will flow from the cylinder 8 through each port 7, nipple 6, chamber 9, ducts 18, 18^a, 18^b, around ball 22, and be discharged through outlet 20, as long as the cylinder remains out of use. Outlet 20 opens into a cross-channel 26 in the casing. The portion of the casing in which the duct 18 is formed overlies the opening 20 and serves to protect the latter against the entry of dirt and the like. As a result, the drain valve 22 will be open at all times except when there is pressure in the cylinder, and the condensate, which forms after blowing off the cylinders, will be discharged instead of accumulating 85 in the cylinder.

The invention exemplifies a combined cylinder cock and automatic drain valve which insures the out flow of the condensate. The cylinder cock and drain valve are combined 100

in a single casing for convenience in installation and maintenance.

The invention is not to be understood as restricted to the details set forth, since these 5 may be modified within the scope of the appended claims, without departing from the spirit and scope of the invention.

Having thus described the invention, what I claim as new and desire to secure by Letters Patent is:

- 10 1. The combination with an engine cylinder, of a casing connected to receive condensate from the cylinder, having a horizontally extending duct, a blow-off cock in the casing and at one end of said duct, and a vertically movable automatic pressure controlled drain-valve in the casing, the other end of said duct extending downwardly and thence inwardly and upwardly to said valve.
- 15 20 2. The combination with an engine cylinder, of a casing connected to receive condensate from the cylinder, a blow-off cock in said casing, an automatic pressure controlled drain-valve in said casing, an upwardly facing outlet leading from the valve, and a duct in the casing extending laterally from the cock and around and under said valve and through which the condensate will escape when the cock is closed.
- 25 30 35 40 3. The combination with an engine cylinder, of a valve casing connected to receive the discharge from the cylinder, a blow-off cock in and at one side of said casing, an automatic pressure controlled drain valve in said casing and adjacent one side of the cock, an upwardly facing outlet from the valve, a transverse duct in the casing into which the outlet discharges, and a duct leading laterally from the cock and around the valve to said outlet.
- 45 50 55 4. An outlet valve of the character described, comprising a horizontally elongated casing provided at one end thereof with a nipple whereby it may be connected to the bottom of an engine cylinder to receive the condensate therefrom, a blow-off cock in said one end of the casing and disposed beneath the nipple, and a vertically movable automatic pressure controlled drain valve in the other end of the casing, said casing having a duct leading laterally from the nipple to said drain valve, and a cross port at the discharge end of the duct into which the condensate from the valve is discharged, said cross port extending entirely through the sides of the casing.

Signed at Chicago, Illinois, this 12 day of May, 1924.

HARRY VISSERING.
